UNITED STATES PATENT OFFICE

114,200

DESIGN FOR A FAUCET

Vincent Joseph Sedlon and Edward W. Pierie,
Cleveland, Ohio

Application February 14, 1939, Serial No. 82,985

Term of patent 7 years

To all whom it may concern:

Be it known that we, Vincent Joseph Sedlon and Edward W. Pierie, citizens of the United States, residing at Cleveland, in the county of Cuyahoga and State of Ohio, respectively have invented a new, original, and ornamental Design for a Faucet, of which the following is a specification, reference being had to the accompanying drawing form part thereof, and in which drawing Figure 1 is a plan view of a faucet showing our new design. Figure 2 is a perspective view of the faucet.

We claim:

The ornamental design for a faucet, as shown.

VINCENT J. SEDLON.

EDWARD W. PIERIE.
